C. Brown & Co.

UNITED STATES PATENT OFFICE.

MATHEW ALSTON, OF ADRIAN, ILLINOIS.

GATE.

SPECIFICATION forming part of Letters Patent No. 514,611, dated February 13, 1894.

Application filed February 6, 1893. Serial No. 461,194. (No model.)

To all whom it may concern:

Be it known that I, MATHEW ALSTON, a citizen of the United States, residing at Adrian, in the county of Hancock and State of Illinois, have invented a new and useful Gate, of which the following is a specification.

The invention relates to improvements in gates.

The objects of the present invention are to simplify and improve the construction of gates, to enable them to be readily counterbalanced to preserve the proper equilibrium, and to facilitate their opening and closing.

The invention consists in the construction and novel combination and arrangement of parts hereinafter fully described, illustrated in the accompanying drawings and pointed out in the claim hereto appended.

In the drawings—Figure 1 is a perspective view of a gate constructed in accordance with this invention; Fig. 2 a sectional view. Fig. 3 is a detail perspective view showing the hanger and pivot bolt. Fig. 4 is a detail perspective view of one of the adjustable weights.

Like numerals of reference indicate corresponding parts in all the figures of the drawings.

1 designates a swinging gate suspended by a hanger 2 and a pivot bolt 3 from a supporting frame, which is composed of opposite posts 4 arranged at each side of the gate and a horizontal top piece 5 secured to and connecting the upper ends of the post. The swinging gate is provided with a rearward extension 6 and a top extension 7, and the hanger 2, which is constructed of metal and which is substantially rectangular in shape, may be secured to the gate by any number of bolts not less than two; said two bolts being arranged to pass respectively through two of the gate-rails to prevent the rocking of the gate within the hanger. The top of the hanger is provided with a perforation to receive the pivot bolt, the head of which is arranged within the hanger; and the bolt 3 extends upward through the top of the supporting frame and is secured by a nut 8 arranged on a washer 9 to protect the wood of the supporting frame. The rearward extension 6 of the gate is narrower than the main portion of the gate to facilitate opening and closing

in winter when snow is on the ground, as the front end of the gate may be elevated without depressing the rear end sufficiently to come into contact with the ground or a drift 55 of snow. On the rails of the extension which are connected by a vertical bar, are mounted adjustable counterbalancing weights 10, which are provided with grooves in their lower faces to receive the rails, and which are adapted to 60 be shifted on the extension to preserve the equilibrium of the gate to prevent sagging and to facilitate opening and closing. The bar serves to prevent the displacement of the weights. The bolt 3 remains stationary and 65 the hanger is swiveled thereon, thus avoiding friction between the bolt and nut and the frame and enabling a nut to be employed for the vertical adjustment of the gate without causing such nut to be loosened and detached 70 by the swinging of the gate.

The top extension of the gate is preferably formed by employing long vertical bars and stretching barbed or other wire on the extension of the bars.

It will be seen that the gate is simple and inexpensive in construction and may be readily opened and closed, and that the proper equilibrium may be preserved.

Changes in the form, proportion and the 80 minor details of construction may be resorted to without departing from the principle, or sacrificing any of the advantages of this invention, as other forms of adjustable weights may be employed for counterbalancing the 85 gate.

What I claim is—

The combination with a supporting frame having a horizontal cross-piece 5, of a pivoted gate having horizontal rails which are extended rearwardly beyond the pivotal point, independent weights slidably fitted upon the extensions of the rails to counterbalance the weight of the main portion of the gate, a hanger 2 secured to the gate by bolts which 90 pass through a plurality of the rails thereof to prevent rocking of the gate within the hanger, said hanger being provided at its upper looped end with a perforation which registers with a perforation in the center of the 95 cross-piece of the supporting frame, and a pivot-bolt engaging said registering perfora- 100

tions and engaged at its upper threaded extremity above the plane of the cross-piece by adjusting nut 8, the lower end of the bolt being headed beneath the surface of the hanger, whereby the latter is swiveled upon and turns freely around the bolt, substantially as specified.

In testimony that I claim the foregoing as my own I have hereto affixed my signature in the presence of two witnesses.

MATHEW ALSTON.
